ELECTRICAL PIEZOMETER APPARATUS

Clarke C. Minter, Washington, D. C., assignor to
 Minter Instrument Corporation, New York,
 N. Y., a corporation of New York

Application December 4, 1947, Serial No. 739,683

4 Claims. (Cl. 201—48)

1

The present invention relates to pressure measuring devices and describes novel apparatus for quantitatively converting mechanical displacements due to pressure changes into equivalent changes in the condition of an electrical circuit and constitutes an improvement over the electrical piezometer shown and claimed in my prior Patent No. 2,358,467, issued September 19, 1944.

The most common means for converting mechanical displacements into changes in an electrical circuit is that in which the mechanical displacement is made to actuate a movable contact sliding over a suitable resistance which is part of an electrical circuit. This type of pick-up is not very satisfactory owing to variable friction at the sliding contact.

In my above noted prior patent the use of sliding contacts is eliminated and I utilize the variation in thermal conductivity of a confined body of gas (helium at 1 mm. pressure) as the volume of a spring-loaded bellows which is varied by external pressure to change the resistance of a current-heated filament forming part of a Wheatstone bridge circuit. The present invention employs the same basic principle, namely, the effect of pressure on the rate at which a current-heated filament loses heat in a confined body of gas. The improvement of the present invention consists in arranging the current-heated filaments in such a manner that when the external pressure decreases, for example, one of the filaments increases in resistance while the other decreases.

The present invention together with the objects thereof may be best understood as the specification proceeds when taken in conjunction with the accompanying drawing wherein:

Fig. 1 is a cross-sectional view showing one form which the present invention may take;

Fig. 2 is a cross-sectional view taken on the line II—II of Fig. 1;

Fig. 3 is a view similar to that of Fig. 1 but showing another modification which the present invention may take;

Fig. 4 is a sectional view taken on the line IV—IV of Fig. 3, and

Fig. 5 is a graph showing the variation in the thermal conductivity of helium with changes in pressure.

Referring now to the drawings in detail, the device as shown in Fig. 1 comprises a cylinder 5, hermetically sealed at one end by a threadedly engaging end plate 6 and having an inlet 7 at its opposite end, to which a conduit or the like from a source of variable pressure, is adapted to

threadedly engage a projecting bib 8. The end plate 6 has an expandable and contractible bellows 9 hermetically sealed to its inner surface leaving the opposite flat end 10 of this bellows free to move. Also welded or otherwise affixed to the end plate 6 is a U-shaped strap or bracket 12 which, at its inner end or base of the U-shape, has secured thereto a second expandable and contractible bellows 13 which is thus disposed within the outer bellows 9. It will also be noted that a further U-shaped strap or bracket 14 is welded or otherwise secured to the movable flat end 10 of the outer bellows 9 and at its other end the strap 14 is secured to the far end 15 of the bellows 13 opposite to the end to which the bracket 12 is connected. Also hermetically sealed through the end plate 6 are a plurality of leading-in conductors 16, 17 and 18, with the conductors 17 and 18 being connected to and supporting a filament 20 within the interior of the outer bellows 9 and the conductors 16 and 18 extending hermetically through the end of the inner bellows 13 and connected to a filament 22 disposed interiorly of the inner bellows 13.

The entire unit as described, being carried by the end plate 6, is accordingly assembled and secured to the end plate prior to insertion in the cylinder 5. After assembly, the bellows 9 and 13, which are designed to have substantially equal free internal volume, so as to compensate for external temperature changes, are then filled with a suitable gas at a pressure of about 1 mm. of mercury and having high thermal conductivity, such as hydrogen or helium, and sealed off at the tips 23. I prefer to employ helium as the filling gas because it is less likely to diffuse through the walls of the bellows. Upon completion of the assembly of the various elements, the end plates 6 carrying such elements, is then screwed into the cylinder 5 in an air-tight manner, by utilization of a suitable gasket 24. Although the complete electrical circuit has not been shown herein, the filaments 20 and 22 may be connected by the leading-in conductors 16, 17 and 18 to the identical Wheatstone bridge arrangement in the same manner as the filaments in my above noted Patent No. 2,358,467, to quantitatively measure pressure variations as therein described.

In the modification of Figs. 3 and 4, the filaments 30 and 32 are mounted in cells or recesses 33 and 34 formed in the end plate 35. Also in this modification the end plate 35 is of slightly larger diameter and threadedly engages an annular collar 36 formed on the cylinder 37 with a

sealing gasket 38 positioned therebetween to make the connection air-tight. A sealed closure 39 constitutes the outer wall of the cells 33 and 34 as well as the outer wall of the end plate 35. In lieu of the inner bellows 40 being supported by a strip or bracket as in Fig. 1, its end 42 is supported from the end plate 35 by a U-shaped hollow tubular member 43 which forms a passageway from the cell 34 to the interior of the inner bellows 40. Also the end plate 35 is provided with a passageway 44 which establishes communication between the cell 33 and the interior of the outer bellows 45. In all other respects the modification of Figs. 3 and 4 is the same as that of Figs. 1 and 2, with the strap 46 tying the movable end 41 of the outer bellows 45 to the end 48 of the inner bellows 40, as previously described relative to Figs. 1 and 2. Also in this latter modification the end plate 35 is provided with four hermetically sealed leading-in conductors 49, 50, 52 and 53, with the leading-in conductors 50 and 52 being connected together externally of the unit instead of internally, as is the common lead 18 of Fig. 1.

Fig. 5 shows how the thermal conductivity of helium varies with pressure with the latter constituting the abscissa and absolute thermal conductivity constituting the ordinate. The line A shows the approximate thermal conductivity of air for comparison purposes while the curve B shows the variation of helium. It will thus be noted that if the pressure of the gas is low (1 mm. of mercury or less), the thermal conductivity thereof varies very rapidly with pressure (density).

Referring again to Figs. 1 and 2 when external gas pressure enters through the inlet 7, it acts on the flat end 10 of bellows 9. The response of the flat end 10 is controlled by the stiffness of the outer bellows 9 and the inner bellows 13 which are so chosen that when the external pressure exceeds 1 mm. Hg absolute, the flat end 10 moves toward the end plate 6. Due to the connection of the straps 14 between the flat bellows end 10 and the end 15 of bellows 13, the flat end 15 is also moved toward the end plate 6, thus expanding the inner bellows 13 to the same degree that the outer bellows 9 is compressed. At the same time the pressure (density) of the gas within the bellows 9 and 13 is compressed and expanded respectively. The compression of the gas within the free space of bellows 9 increase its thermal conductivity, as can be seen by reference to Fig. 5, with the result that the current heated filament 20, which may be connected to a Wheatstone bridge arrangement, will lose heat at a faster rate thus causing its temperature and electrical resistance to decrease in proportion to the increase in pressure exerted on the flat end 10 of the bellows 9.

The simultaneous expansion of bellows 13, due to movement of its end plate 15 by the U-shaped strap 14 causes a decrease in the gas pressure within the bellows 13 thereby decreasing the thermal conductivity of the gas. This in turn results in the heated filament 22, which may likewise be connected to the Wheatstone bridge arrangement, losing heat at a slower rate and causing an increase in the temperature and resistance of the filament 22. Thus the filaments 20 and 22 are inversely responsive to pressure changes exerted on the flat bellows end 10 and by connecting these filaments in a Wheatstone bridge arrangement, as shown in my above noted prior patent, such pressure changes can be readily

indicated on a suitable meter, or the changes in the resistance of the filaments utilized to automatically operate machinery or the like.

When the external pressure is about 1 mm. Hg the two bellows 9 and 13 are completely relaxed, due to the internal gas pressure of the helium being so chosen that the total inward force exerted by the pressures within bellows 9 and 13 on the flat bellows end 10, is equal to the external force exerted on this bellows end 10. This means that

$$PA_{10} = P_9 A_{10} + (P_9 - P_{13}) A_{15}$$

in which P is the external pressure applied to bellows end 10, P_9 is the pressure in bellows 9 P_{13} is the pressure in bellows 13 and A_{10} and A_{15} are the area of the respective bellows end plates 10 and 15.

As the external pressure increases, the bellows end 10 moves toward the end plate 6 and at a pressure depending upon the combined stiffness of the bellows 9 and 13, until the angular projection of the U-shaped strap 14 affixed to the inside of bellows end 10, contacts the fixed end of the inner bellows 13, when any further increase in pressure thereafter produces no further changes in the resistance of filaments 20 and 22.

Accordingly, the range of pressure to which the unit is responsive is controlled by the stiffness of the bellows 9 and 13 together with the spacing between the angular projection of the U-shaped bracket 14 relative to the fixed end of the bellows 13, when the bellows 9 and 13 are in relaxed condition, with the maximum displacement of the bellows ends 10 and 15 depending on the elastic limit of the bellows 9 and 13.

The modification of Figs. 3 and 4 operates in the identical manner as that above described, the only difference being that the filaments 30 and 32 of this modification are not within the confines of the respective bellows 40 and 45. Instead, the pressure changes within the bellows 45 are transmitted to the filament 30 through the passageway 44 and in a similar manner, the pressure changes within the inner bellows 40 are transmitted to the filament 32 through the hollow tubular support member 43.

It thus becomes obvious to those skilled in the art that an electrical piezometer unit is herein provided which is exceedingly sensitive in its operation. By the utilization of electrically heated filaments subjected to changes in pressure of a fluid having high thermal conductivity, the temperature and hence the electrical resistance of these filaments is simultaneously varied inversely proportional to changes in pressure of an external force. Thus by suitably connecting these filaments in a measuring or a control circuit, the circuit is thus responsive to external pressure changes which can be accurately measured or employed to accurately control machinery and the like.

Although one specific embodiment of the present invention has been shown and described, it is to be understood that still further modifications thereof may be made without departing from the spirit and scope of the appended claims.

I claim:

1. Apparatus for converting mechanical displacements of a flexible member into equivalent changes in the condition of elements of an electrical circuit comprising two bodies of helium gas each at a preselected density and independently confined in the free internal volumes of two sensitive bellows having their fixed ends

suitably attached to a base plate and their free pressure-responsive ends connected together, a conducting filament mounted in each of said two bodies of helium gas, and means for connecting said conducting filaments into an electrical circuit.

2. Apparatus for converting mechanical displacements of a flexible member into equivalent changes in the condition of elements of an electrical circuit, comprising two bodies of helium gas, each at a preselected density and independently confined in the free internal volumes of two unequally sensitive bellows, the smaller being suitably mounted inside the larger with the fixed ends of both of said bellows suitably attached to the same base and their free pressure-responsive ends connected together, a conducting filament mounted in each of the said two bodies of gas, and means for connecting said conducting filaments into an electrical circuit.

3. Apparatus for converting mechanical displacements of a flexible member into equivalent changes in the condition of elements of an electrical circuit comprising two bodies of helium gas, each at a preselected density and independently confined in the free internal volumes of two unequally sensitive bellows, each of said bellows communicating through suitable conduits with two similar closed cells, a conducting fila-

ment mounted in each of said cells, and means for connecting said filaments into an electrical circuit.

4. Apparatus for converting mechanical displacements of a flexible member into equivalent changes in the condition of elements of an electrical circuit comprising two bodies of helium gas, each at a preselected density and independently confined in the free internal volumes of two unequally sensitive bellows, the smaller being mounted inside the larger with the fixed ends of both of said bellows attached to the same base plate and their free pressure-responsive ends connected together, two similar closed cells, two passageways each of which connects the interior of one of said bellows with one of said closed cells, a conducting filament mounted in each of said cells, and means for connecting said conducting filament into an electrical circuit.
